UNITED STATES PATENT OFFICE

163,944

STOCKING

Barnett D. Gordon, Brookline, Mass.

Application November 28, 1950, Serial No. 13,155

Term of patent 14 years

(Cl. D47—7)

To all whom it may concern:

Be it known that I, Barnett D. Gordon, a citizen of the United States, residing at Brookline, in the county of Norfolk and State of Massachusetts, have invented a new, original, and ornamental Design for a Stocking, of which the following is a specification, reference being had to the accompanying drawings, forming part thereof.

Figure 1 is a side elevational view of a stocking, showing my new design.

Figure 2 is a fragmentary heel end elevation of the same.

I claim:

The ornamental design for a stocking, as shown.
BARNETT D. GORDON.
